UNITED STATES PATENT OFFICE.

ALEXANDER FERDINAND VICTOR, OF DAVENPORT, IOWA.

STEREOPTICON SCREEN.

Application filed February 12, 1923. Serial No. 618,632.

My invention relates to stereopticon screens, and its object is to provide a screen that can be utilized in the daytime as well as at night, and which can be knocked down and folded into a compact form and transported from place to place, and easily be set up anywhere for use. This I accomplish by the means hereinafter fully described and as particularly pointed out in the claims.

10 In the drawings:

Figure 1 is a perspective view of my invention showing the stereopticon in place.

Figure 2 is a side view of the same folded, and with the stereopticon removed.

15 Figure 3 is a longitudinal section taken on dotted line 3, 3, Figure 4.

Figure 4, is a horizontal section taken on dotted line 4, 4, Figure 3.

Figure 5 is a top view of the folded screen, drawn to the same scale as Figures 1 and 2.

Figs. 6 and 7 are sectional details showing respectively the manner of hinging the shelf at the front of the structure and for supporting the arms at the rear. Fig. 8 is a detail of the lower support for the mirror. Fig. 9 is a vertical section on line 9—9 of Fig. 10. Fig. 10 is a detail of the upper support for the mirror.

20 Referring to the drawings A represents a rectangular screen, the side members *a*, *a*, of the frame enclosing which are extended down a sufficient distance to form the front legs of the screen, and B, B, represent rectangular sidewalls that have their rear vertical edges formed with vertical pieces that are rectangular in cross-section that are extended down below the lower edges of the same, the same distance as the legs *a*, to 25 form rear legs *b*, *b*. The legs *b*, *b*, are, preferably, nearer together than the legs, *a*, *a*, and in horizontal section form the angles of a quadrangle figure. The screen A is formed of translucent material that is suitably secured in a rectangular frame, and the sidewalls are made of wood with their top and bottom and rear sides enclosed in a frame, the parts of which are, in cross-section, of substantially the same dimensions 30 as the vertical members of the legs thereof. The forward ends of the top and bottom members 5 and 6 are hinged to the front legs *a*, *a*, of the screen, the left hand wall, looking at it from the front of the screen, is hinged at 7 to the surface of the left hand

leg, and the right hand wall is hinged by a double hinge 8 to the front surface of the right hand leg, substantially as shown in Figure 4 of the drawings.

When folded the left hand wall will fold flat against the rear of the screen, substantially as shown by the dotted line 9, and the right hand wall will fold flat against the front of the screen into the position, shown in Figure 2 of the drawings.

At a short distance below the screen and sidewalls, the front legs *a* are connected by a cross-bar 11. The rear legs *b*, have longitudinal rails 13 permanently secured thereto, and the forward ends of these rails are 40 connected by hinges, X, similar to 7 and 8 to front legs *a*, *a*.

Next the rear legs *b*, *b*, bars 13 are loosely connected by a transverse strip 14, the ends of which latter are clamped by a flat spring-clamp 15, 15, and held in close contact with bars 13, and this transverse piece or strip 14 supports the rear ends of the rearwardly projecting parallel arms 16, 16, whose forward ends pass under and are hinged to cross-bar 11, and project forward beyond said bar 11 and are connected by a transverse shelf 17. When folded upright parallel to the front legs *a* the arms may be maintained thus by hooks and eyes 12, 12. 50 This shelf is immediately in front of said cross-bar 11 and it has a couple of guards, 18, 18, that consist of wedge shaped strips, between which a stereopticon C is placed.

This stereopticon C may be of any of the well known type, although I prefer it to be cylindrical, and when in position, it is inclined so as to direct images as shown by dotted line 19 in Figure 3 of the drawings, against the center of a mirror reflector 20.

Mirror 20, is, preferably, rectangular, and is set and secured in an outside rectangular frame of wood or metal. The upper horizontal member 21 of this reflector is hinged to the front edge of a transverse member 22, the ends of which have studs 23 projecting transversely therefrom, that have heads that are adapted to catch behind the vertical bifurcations 24 of the somewhat X-shaped plate 25, the portion of which below member 22, is secured by screws 26 or otherwise to the opposing surfaces of the rear legs *b*, near the upper edge of the side-walls B. The lower corners of the reflector 20 are provided with downwardly projecting bi-

furcated plates 27, and the bifurcations of these plates, when the reflector is set in place, are made to straddle the headed pins or screws, screwed into the opposing surfaces of said legs, at a point slightly above the plane of the lower members of the sidewalls.

Member 22 is such width that when the reflector is secured in the manner stated, 10 it will incline forward from its upper end and will reflect any image that may be projected thereto from the stereopticon, to the center of the screen, as shown by dotted line 29 in Figure 3 of the drawings.

15 By lifting member 22 so that, first, the studs 23 can be removed from between the bifurcations 24 of plate 25, and, second, by lifting the plate 27 off of pins 28, and, third, also by removing the cross-bar 11 from between the legs *a*, and withdrawing the rear ends of the arms 16, 16, off of the transverse strip 14, and, finally, by withdrawing said strip 14 from under the spring-clamps 15, the sidewalls B can be folded against 20 the screen A in the manner hereinbefore stated. When this is done the shelf and the cross-bar 11 are folded against the folded screen and sidewalls and the reflector 25 is placed against the same, so as to make 20 a flat package that can be easily clamped together and transported from place to place.

What I claim as new is:

1. A screen structure for stereopticons 35 comprising a translucent screen, a frame surrounding the same having its vertical members extending below the same to provide legs, sidewalls hinged thereto and extending rearwardly therefrom the rear vertical members of which are extended downwards to provide legs, a reflector at the rear of the screen between said sidewalls and means below the screen for supporting the stereopticon which latter is focused on 40 said screen.

2. A screen structure for stereopticons comprising a translucent screen, a frame surrounding the same having its vertical members extended below the same to provide legs, 50 sidewalls hinged thereto and extending rearwardly therefrom the rear vertical members of which are extended downwards to provide legs, a reflector at the rear of the screen between said sidewalls, and a shelf below the screen for supporting the stereopticon which latter is focused on said screen.

3. A screen structure for stereopticons comprising a translucent screen, a frame surrounding the same having its vertical members extended below the same to provide legs, sidewalls hinged thereto and extending rearwardly therefrom the rear vertical members of which are extended downwards to provide legs, a reflector at the rear of the screen 65 between said sidewalls and a movable shelf

below the screen for supporting the stereopticon which latter is focused on said screen.

4. A screen structure for stereopticons comprising a translucent screen, a frame surrounding the same having its vertical members extended below the same to provide legs, sidewalls hinged thereto and extending rearwardly therefrom the rear vertical members of which are extended downwards to provide legs, a reflector at the rear of the screen between said sidewalls, a cross-bar connecting the front legs below the screen, and a shelf upon which the stereopticon is placed and focused upon said screen. 70 75

5. A screen structure for stereopticons 80 comprising a translucent screen, a frame surrounding the same having its vertical members extended below the same to provide front legs, sidewalls hinged thereto and extending rearwardly therefrom whose rear vertical members are extended downwards to provide rear legs, a reflector at the rear of the screen and between said sidewalls, a removable cross-bar connecting the front legs below the screen, and a shelf having a 85 hinged connection to said bar upon which the stereopticon is placed and focused upon said screen. 90

6. A screen structure for stereopticons 95 comprising a translucent screen, a frame surrounding the same having its vertical members extended below the same to provide front legs, sidewalls hinged thereto and extending rearwardly therefrom whose rear vertical members are extended downwards to provide rear legs, a reflector at the rear of the screen and between said sidewalls, a movable cross-bar connecting the front legs below the screen, longitudinal rails connecting said front legs and said rear legs, a 100 shelf having a hinged connection to said bar upon which the stereopticon is placed and focused upon said screen, an arm projecting rearwardly from said shelf, a transverse piece resting upon said rails and upon 105 which the rear portions of said arms rest. 110

7. A screen structure for stereopticons comprising a translucent screen, sidewalls hinged thereto and extending rearwardly 115 therefrom, a transverse member connecting the rear portions of said sidewalls, a reflector the upper portion of which is connected to said transverse member, devices to which the lower portions of said reflector is connected, and means below said screen 120 for supporting the stereopticon, which latter is focused on said screen.

8. A screen structure for stereopticons comprising a translucent screen, sidewalls hinged thereto and extending rearwardly 125 therefrom, a transverse member removably connected to the rear portions of said sidewalls, a reflector the upper portion of which is hinged to said transverse member, devices to which the lower part of said reflector 130

is connected, and means below said screen for supporting the stereopticon which latter is focused on said screen.

9. A screen structure for stereopticons comprising a translucent screen, sidewalls hinged thereto and extending rearwardly therefrom, a transverse member removably connected to the rear portions of said sidewalls, a reflector the upper portion of which is hinged to said transverse member, bifur-

cated plates secured to said rear legs, pins projecting from the lower portion of said reflector that enter the space between said bifurcations, and means below said screen for supporting the stereopticon which latter is focused on said screen.

In witness whereof I have hereunto set my hand this 6th day of Oct., 1922.

ALEXANDER FERDINAND VICTOR.
